H. A. Kroeger
INVENTOR

BY *Victor J. Evans*
ATTORNEY

UNITED STATES PATENT OFFICE.

HATTIE A. KROEGER, OF WALCOTT, IOWA.

CABINET.

Application filed March 12, 1921. Serial No. 451,770.

To all whom it may concern:

Be it known that I, HATTIE A. KROEGER, a citizen of the United States, residing at Walcott, in the county of Scott and State 5 of Iowa, have invented new and useful Improvements in Cabinets, of which the following is a specification.

This invention relates to cabinets and more particularly to a cabinet designed for 10 storing player piano rolls.

Quite frequently dwellings wherein player pianos are located have not sufficient room to permit the use of an ordinary cabinet for storing player piano rolls and it is an object 15 of this invention to provide a cabinet structure which is designed to be placed upon the top of a player piano for retaining the record rolls of the piano and one which will not detract from the artistic appearance but 20 will increase the convenience of playing a player piano in that it will be unnecessary for the operator to leave his seat at the piano to get a new roll or replace a played one in the cabinet.

Other objects of the invention will appear 25 in the following detailed description and in the accompanying drawing wherein:

Fig. 1 is a fragmentary view of a player piano showing the improved cabinet mounted thereon.

Fig. 2 is a cross section through the cabinet taken on the line 2—2 of Fig. 1.

Fig. 3 is a detail horizontal section taken on the line 3—3 of Fig. 1.

Fig. 4 is a detail enlarged view of a portion of track.

Referring more particularly to the drawing the improved cabinet comprises two sections 1 and 2, each of which is identical in 40 construction. The cabinet is made in sections for convenience in handling and use and the two sections are constructed so that their facing ends will abut in snug engagement and provide a pleasing appearance.

Each of the sections 1 and 2 is rectangular 45 in shape, and its height may be regulated as desired depending upon the number of rolls to be retained therein. Guiding rails 8 are positioned at each end of the sections 50 near their tops and have upturned hook shape forward ends 4 spaced from the top. The front panels or doors 5 of the sections

are constructed in any artistic design to add the aesthetic properties of the cabinet and they have rollers 6 supported at each upper 55 corner which ride upon the guide rails 3 and support the front panels or doors either in open or closed position above the rails. The rollers 6 preferably have rubber or analogous resilient material upon their perimeters 60 to prevent undesirable noise when opening or closing the cabinet. The rollers 6 engage against the concave surface of the upturned hook shaped ends 4 of the guide rails 3 which limits the outward horizontal movement of the panels or doors 5 and provides pivots upon which the panels are swung into their vertical closing position. To open either of the sections of the cabinet the door 70 or front panel is moved forward on its pivot formed by the rollers 6 and ends 4 until it is in a substantially horizontal position when it is moved rearwardly into the cabinet, similar to the movement of the closure of a book case and thus access is had to the interior of the cabinet section. A plurality of knobs or handles 7 are attached to each of the front panels or doors 5 to facilitate the convenient opening or closing of same and cushioning feet or buttons 8 are attached to 80 the under surface of the bottoms of the sections 1 and 2 to prevent marring of the finish of the top of the player piano upon which the cabinet is mounted.

It is, of course, to be understood that the 85 invention may be constructed in various other manners and the parts associated in different relations and, therefore, I do not desire to be limited in any manner except as set forth in the claim hereunto appended. 90

Having thus described my invention what I claim is:

In combination, a cabinet, hollow tracks secured to the ends thereof spaced from the top of the cabinet, the forward ends of the 95 tracks being bent upwardly above the tracks, a door in the cabinet and rollers secured to the door in position to move in said tracks and to be forced upwardly in the forward ends of the tracks in the closing of the door 100 and thereby lock the door.

In testimony whereof I affix my signature

HATTIE A. KROEGER.
